UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC SWITCH.

1,194,345.

Specification of Letters Patent.

Patented Aug. 8, 1916.

Application filed August 8, 1912. Serial No. 712,047.

To all whom it may concern:

Be it known that I, CHARLES J. KLEIN, a citizen of the United States, residing at Milwaukee, in the county of Milwaukee and State of Wisconsin, have invented new and useful Improvements in Electric Switches, of which the following is a full, clear, concise, and exact description, reference being had to the accompanying drawing, forming 10 a part of this specification.

My invention relates to electric switches.

It has among its objects to provide an improved electric switch which is especially adapted to use as a pendant switch, wherein, 15 by the improved arrangement and construction of parts, the device may be made to assume a very compact and convenient form and may be manufactured at small expense.

Other objects and advantages of my invention will hereinafter appear.

In order to clearly and fully disclose my invention, I have illustrated one form of the same in the accompanying drawings. It is to be understood, however, that the form 25 illustrated is susceptible of modification.

Figure 1 shows a central vertical sectional view of the switch and casing therefor. Fig. 2 is a top plan view of the construction shown in Fig. 1, the cap being removed. 30 Fig. 3 is a bottom plan view of the switch device, the casing being shown in section.

I have shown a push button operated snap switch mechanism carried upon the bottom of an insulating base and supported in a pendant switch casing so that the operating members of the switch mechanism extend through the sides of the casing and the terminal connections for the switch mechanism are located upon the top of the base in such 40 a position as to be readily accessible upon removal of the cap from the casing.

The switch mechanism is of the type described and claimed in my co-pending application, Serial No. 622,903, filed Aug. 6, 1912, 45 wherein a push button operated member 1 is provided with a pair of concave and convex cams 2 and 3, which, upon the reciprocation of the member 1, actuate a movable contact 4, pivoted on a spindle 5, to compress a coiled spring 6 which, at a predetermined time, turns said contact with a quick snap action to make or break the circuit at stationary resilient contacts 7 and 8. This 55 switch mechanism is carried upon the bottom face of a substantially disk-shaped in-

sulating base 9 formed of one piece of insulation. The bottom surface of this face is provided with a recess 10 in which the switch mechanism is mounted, a pedestal 11 being provided at the center of the base to receive the spindle 5. As shown in Fig. 3, the contacts 7 and 8 are carried in slightly deeper recesses on opposite sides of the base and the wall or flange 12 around the recess 10 is provided with oppositely located slots or openings 13 through which the push buttons extend. The terminal connections for the switch mechanism are carried upon the opposite or upper face of the base in a shallow recess 14, screws 15 and 16 extending from the contacts 7 and 8 through to the top of the base and there being attached to terminal plates 17 and 18, carrying binding screws 19 and 20.

The base 9 is carried in a two-part casing comprising a shell 21 and a cap 22. These two parts are arranged to be snapped together to lock them against longitudinal separation, suitable catches 23 being provided upon the upper end of the shell 21 and 25 adapted to snap over an annular flange 24 upon the cap 22. In order to prevent the relative rotation of the two parts of the receptacle, the interfitting ends of the same are made polygonal as shown in Fig. 2. The shell 21 is substantially cup shaped, being provided with a rounded bottom as shown. This member when united with a cap 22, forms a receptacle of substantially acorn shape. The switch mechanism is insulated 30 from the sides of the member 21 by the base 9 and from the lower end of the same by means of an insulating lining 25 which is held in position by downwardly extending struck-in portions 26 located substantially 35 beneath the push buttons. The cap 22 of the casing is insulated by means of an insulating lining 27 carried within the same by means of an insulating bushing 28 which is provided with a flange 29 on its lower end 40 adapted to hold the same in position. As illustrated in Fig. 1, vertically extending slots 30 are provided in the opposite sides of the part 21 to permit the switch mechanism to be slipped into position and to allow 45 the reciprocation of the push buttons. As shown in Fig. 2, the base 9 is provided with a pair of oppositely extending lugs 31 located above the push buttons and adapted to be received in the upper end of the slots 30. 50

It is to be noted that the edges of the slots are overturned as at 32 when they abut against the sides of the lugs 31.

In my improved construction the base is formed of a single piece of insulation which may be very readily and cheaply molded into exceedingly compact form. The depending flange upon the same also serves to insulate the switch mechanism from the inner closing casing. Further, the terminals for the device are located in such a position that they are very readily accessible, since it is only necessary to remove the cap to gain access to the same. Further, these terminals are separated from the switch mechanism by a solid wall of insulation. The casing is likewise effectually insulated from the switch mechanism and is of a compact construction which presents an exceedingly neat and pleasing appearance.

What I claim as new and desire to secure by Letters Patent of the United States is:—

1. In a pendent switch, in combination, a casing comprising a cupped shell and a cap therefor having a conductor opening, an insulating base transversely supported within said shell, said base having a substantially continuous depending peripheral flange af-

fording a central recess, a snap switch mechanism mounted in said recess and insulated from said shell by said flange, said mechanism including a push button operating member projecting through said flange and a contactor pivoted medially and movable in a plane substantially parallel to the plane of movement of said operating member, and binding posts for said mechanism mounted upon the upper face of said base and beneath said cap.

2. In combination, a casing comprising a cup-shaped shell and a cap therefor, an insulating base within said shell having a depending peripheral flange forming a chamber, an insulating lining in said cap extending to said base and an insulating lining in said shell extending to said flange, and a snap switch mechanism mounted on said base and within said chamber.

In witness whereof, I have hereunto subscribed my name in the presence of two witnesses.

CHARLES J. KLEIN.
